H. H. EMMONS

VALVE

Filed Oct. 28, 1921

FIG. 1.

FIG. 2.

FIG. 3.

Inventor

H. H. Emmons

By

John P. Duffie

Attorney

UNITED STATES PATENT OFFICE.

HARRY H. EMMONS, OF ALLIANCE, OHIO.

VALVE.

Application filed October 28, 1921. Serial No. 511,120.

To all whom it may concern:

Be it known that I, HARRY H. EMMONS, a citizen of the United States, residing at Alliance, in the county of Stark and State 5 of Ohio, have invented certain new and useful Improvements in Valves, of which the following is a specification.

This invention relates to new and useful improvements in valves and more especially 10 to valves of the faucet or spigot type.

The principal object of my invention is to provide a valve with an adjustable nozzle which automatically opens the valve when swung into operative position and shuts the 15 valve off when folded or swung back into an inoperative or out-of-the-way position.

With the foregoing and other objects in view that will readily appear as the nature of the invention is better understood, the 20 same consists in the novel features of construction, combination and arrangement of parts illustrated in the accompanying drawings and more particularly pointed out in the appended claim.

25 In the accompanying drawings, which are for illustrative purposes only and are therefore not drawn to scale,

Figure 1 is a perspective view of a valve of the faucet or spigot type, illustrating the 30 application of my invention.

Figure 2 is a central longitudinal section of Figure 1 and Figure 3 is a reverse plan view of Figure 2.

Referring to the drawings for a more particular description of my invention and in 35 which drawings like parts are designated by like reference characters throughout the several views, the numeral 1 represents the valve casing, 2 the valve and 3 the nozzle.

40 The valve casing 1 is provided with a central longitudinal bore or passage 5, adapted to register with the lower end of a longitudinally disposed bore or passage 6 formed in the upper end of the cone-shaped valve 7.

45 Valve 7 works in a corresponding vertical opening 8 in the casing 1 and is formed at its upper end with a square head 10, which projects above the top of the casing and is adapted to fit in a corresponding socket 10¹ formed in the cylindrical head 11 held to the head 10 by a set-screw 11¹. The head 11 is formed at the inner end of the nozzle 3,

50 which is in the form of a straight hollow tube with a downwardly bent front portion 55 or spout 12.

The valve casing 1, which is of general

rectangular form, is provided at its inner end with an interiorly threaded socket 13 for screw threaded connection with the water or supply pipe (not shown). The bottom of 60 the casing is also provided with a drain opening 14, which communicates with the bore or passage 5 and is normally closed by the threaded plug 15.

In carrying out my invention, the valve 65 casing 1, is provided at its inner end on its top wall 16, with a raised shoulder or boss 17 formed with a flat upper face 18 and provided at opposite edges with apertured lugs 19 adapted to receive fastening screws 70 or other equivalent means (not shown) employed in fastening or securing the valve casing in place.

Among the numerous advantages to be derived through the use of my invention, some 75 of the more important may be briefly enumerated as follows:—

First: The valve is closed when the nozzle is in a folded or out-of-the-way position, as illustrated by dotted lines in Figure 1, and 80 automatically opens the valve when swung into operative position by giving it a quarter turn.

Second: A workman in close quarters may 85 push aside the nozzle when not in use.

Third: Is especially valuable as an automobile lavatory spigot as the same may be fastened under the running board of the machine, is always ready for instant service when connected to a supply tank either of 90 water or other liquid and is invisible when not in use.

Fourth: Is efficient and tends to economize 95 liquids for the reason that unless the nozzle is turned under the shelf or other support, it is a notice to all that it is being used.

The flat upper face 18 of the shoulder or boss 17, is adapted to fit squarely against the running board of an automobile, a shelf or other support and the apertured lugs 19 provide means for receiving the fastening screws or other equivalent means (not shown). It will be noted that the upper surface 18 of the boss 17 is disposed in a plane slightly above the upper edge of the 100 nozzle to allow the latter to be freely turned in either direction without any tendency to bind against the shelf or other support.

105 It will be understood that my valve improvements may be applied to a valve of any 110 type where it could be used to advantage.

From the foregoing description taken in

connection with the drawings, it is thought that the construction, operation and advantages of my invention will be readily understood without requiring a more extended 5 explanation.

Having described my invention, what I claim as new and desire to secure by Letters Patent, is:—

In combination, a valve casing, a valve 10 rotatable therein, a nozzle connected with and adapted to be used as a handle or lever in turning the valve, said nozzle adapted

to open the valve when in extended or operative position and to close the valve when in a folded or out-of-the-way position and a 15 raised shoulder or boss formed on the top of the valve casing, said boss provided with a flat upper face disposed in a plane above that of the upper edge of the nozzle and having apertured lugs disposed at opposite 20 edges thereof.

In testimony whereof I affix my signature.

HARRY H. EMMONS.
